UNITED STATES PATENT OFFICE.

FRANK L. FORWARD, OF NYACK, NEW YORK, ASSIGNOR TO UNIVERSAL PLANER COMPANY, INC., A CORPORATION OF DELAWARE.

PORTABLE PLANING-MACHINE.

1,337,350.

Specification of Letters Patent. Patented Apr. 20, 1920.

Application filed March 14, 1918. Serial No. 222,357.

To all whom it may concern:

Be it known that I, FRANK L. FORWARD, a citizen of the United States, residing at Nyack, in the county of Rockland and State 5 of New York, have invented certain new and useful Improvements in Portable Planing-Machines, of which the following is a specification.

This invention relates to improvements in 10 planing machines and it is the principal object of the invention to provide a novel rotary planing machine so constructed as to permit its use for planing plane or curved surfaces in a rapid and effectual manner, 15 the machine being portable and exceedingly light and compactly constructed, thus, rendering the same desirable for use in connection with various grades of work.

Another and equally important object of 20 the invention is to provide the machine with a form of flexible base which can be varied in shape to accord with the contour of the surface to be planed thereby.

Other objects will be in part obvious and 25 in part pointed out hereinafter.

The invention consists, furthermore, in the novel arrangement and combinations of the parts of the machine, as well as in the details of the construction of the same, all 30 of which will be more fully described in the following specification and then finally embodied in the clauses of the claim which are appended to this specification and which form an essential part of the same.

35 In the drawings:

Figure 1 is a side elevation of the machine having parts shown in section,

Fig. 2 is a fragmentary detail partly in 40 section showing the mounting of the rotary planing knives,

Fig. 3 is a fragmentary detail showing the connection between the screw threaded shanks and the flexible base, and

Fig. 4 is a horizontal section there- 45 through.

Having more particular reference to the drawings, in connection with which like reference characters will designate corresponding parts throughout the several 50 views, 1 represents the frame of the improved machine, the opposite ends of which are apertured and receive screw threaded bushings 2 therein, through which pivotal screw threaded shanks 3 are passed, these 55 shanks, as will be noted, being pivotally

connected as at 4 to the flexible base 5 of the machine, which base is formed with a suitable opening for permitting the rotary knives of the machine to be engaged with a surface being planed thereby. Handle 60 pieces or knobs 6 are engaged with the upper portions of the several screw threaded bushings 2 by means of screws 7 or similar fastening devices and as will be noted are provided with vertical bores alining with 65 the screw threaded openings formed in their respective bushings 2. Obviously, these knobs serve as means for facilitating rotation of the bushings 2 and as a consequence, vertical adjustment of the same and the ad- 70 jacent ends of the flexible base 5 with relation to the opposite ends of the frame 1.

A hollow casting indicated in its entirety by the numeral 8 is secured to the inner side of the flexible base 5 at a point in proximity 75 to the knife receiving opening formed therein and as will be noted, is provided with cradles 9, on which the lower portion of the casing of a motor designated by the numeral 10 rests; said motor, being ar- 80 ranged in a suitable seat formed in the frame 1 and secured to said frame by means of set screws 11 or similar fastening devices which are passed through segmented flanges formed on the adjacent marginal portions 85 of the frame.

Mounted in the lower portion of a hollow casting 8 are the rotary planing knives 12, the same, obviously, being arranged on a transversely disposed shaft 13 having its 90 opposite ends journaled in suitable bearings formed in an adjustable sub-frame 12', which as will be noted, is secured to the flexible base 5 by a spring metal strip 13', the free end of the frame being engaged by adjust- 95 ing screws 14'. One of the ends of the shaft 13 is extended and has a gear 14 fixedly mounted thereon which gear meshes with an idler 15 also mounted on suitable bearings arranged in the casting 8, and being of 100 a size greater than the gear 14. The adjacent end of the rotatable armature shaft of the motor is provided with a gear 16 which normally meshes with the idler gear 15, thus permitting the transmission of ro- 105 tary motion to the planing knives 12 when the motor is energized. It is of course to be understood, that suitable conductors are ex- tended into engagement with the contact terminals of the motor and are in turn, 110

connected to a source of supply, whereby the necessary electrical energy may be conducted to the motor. Further, if desired, a switch 17 of any desired type may be arranged on 5 the motor and interposed in certain of the electrical conductors as indicated at 21 whereby to control the closing of the circuit through the coils of said motor.

A curved oil tube 18 is secured to the casting 8 adjacent one of the cradles 9 thereof and has its lower end communicating with the bearings of the gear 14, while the upper end is extended to a convenient point whereat oil may be introduced thereinto. The motor 15 too, is provided with a suitable form of grease cup 19, which is adapted to feed lubricant to the bearing surfaces of the same, thus, insuring proper functioning of the same at all times.

20 To facilitate the handling of the machine, that is, the moving of the same over a surface to be planed, a handle 20 may be and preferably is secured to the rear portion of the frame 1 in a suitable manner.

25 In operation, the flexible base 5 is adjusted to conform to the contour of a surface to be planed by the machine, whereupon the switch 17 is closed, thus starting the motor 10 and permitting the transmission of rotary 30 motion by way of the various gears to the rotatable cutting knives 12. The machine is now moved over the surface to be planed thereby. Obviously, by adjusting the flexible base 5 by means of the knobs 6 and screw 35 threaded bushings 2 which are secured thereto, said base may be varied in shape to conform to either plane or curved surfaces and as a consequence, the machine may be adapted for use in connection with different 40 kinds or grades of work.

I of course desire to have it understood

that different forms of gearing other than that shown, as well as the different type of cutting knives may be employed, should it become necessary, in order that the machine 45 may properly perform its operation; further, that the specific form of drive means or motor may be varied, such as conditions or preference may dictate; that is, the machine, should it be desired, may be driven 50 by an air motor or like mechanism.

As hereinbefore indicated, I do not wish to be understood as confining the invention to the particular embodiment chosen for illustration herein, nor to the exact construction, arrangement and adaption of parts shown and described, but I reserve the right to make any changes and alterations that fairly fall within the spirit and scope 60 of the invention.

I claim:

An apparatus for planing curved surfaces which comprises in combination a main frame and motor mounted therein, a flexible base strip attached to said main frame 65 and means for adjusting the same to fit the curvature of the surface to be planed, said base having a transverse slot through which the cutting knives may operate, a rotary cutter geared to the motor, and a sub frame in 70 which said cutter is journaled, a spring metal strip fastened near one edge to the main frame and near the other edge to one end of the sub frame so as to form a hinge support for the latter, and a screw mounted 75 in the main frame and forming an adjustable support for the other end of the sub frame.

In testimony whereof, I affix my signature hereto.

FRANK L. FORWARD.
